PORTABLE SEESAW

Harry F. Husted, Benton, Pa., assignor to Tittisanna A. Morie, Tomhichena, Pa.

Application October 18, 1935, Serial No. 45,656

10 Claims. (Cl. 272—54)

This invention relates to a portable seesaw, and has for one of its objects to provide, in a manner as hereinafter set forth, a device of the class referred to to insure for satisfactory teetering when the device is used by persons of different weights.

A further object of the invention is to provide, in a manner as hereinafter set forth, a device of the class referred to including a pair of carriers, one capable of being angularly adjusted relative to the other for decreasing its leverage without changing that of the other whereby a satisfactory teetering action is had when the device is used by persons of different weights.

15 A further object of the invention is to provide, in a manner as hereinafter set forth, a device of the class referred to including means to provide for a satisfactory teetering action when the device is used by an adult and a child.

20 A further object of the invention is to provide, in a manner as hereinafter set forth, a pair of oppositely disposed tiltable carriers mounted upon a common pivot and each including a seat structure and equalizing means for the latter and with 25 the said means of the carriers being mounted at one end on a common pivot and at their other ends pivotally connected to the seat structures.

A further object of the invention is to provide, in a manner as hereinafter set forth, a detachable pivoting coupling connection for each end 30 of the equalizing means of a carrier.

Further objects of the invention are to provide, in a manner as hereinafter set forth, a seesaw which is comparatively simple in its construction and arrangement, strong, durable, compact, portable, capable of being readily adjusted for use by two persons of different weight to insure for satisfactorily teetering, readily assembled, conveniently repaired when occasion requires 40 and comparatively inexpensive to manufacture.

With the foregoing and other objects in view, the invention consists of the construction, combination and arrangement of parts as will be more specifically referred to and as are illustrated in the accompanying drawings wherein there is shown an embodiment of the invention, but it is to be understood that changes, variations and modifications may be resorted to which fall within the scope of the invention as claimed.

50 In the drawings:

Figure 1 is a side elevation of the seesaw and further illustrating, in dotted lines, one of the carriers angularly adjusted with respect to the 55 other,

Figure 2 is a top plan view of the seesaw, Figure 3 is a section on line 3—3, Figure 1, on an enlarged scale,

Figure 4 is a section on line 4—4, Figure 3,

Figure 5 is a detail in front elevation showing 5 the form of coupling plate employed by the carriers,

Figure 6 is a detail in sectional plan of a carrier,

Figure 7 is an edge view of the plate shown in 10 Figure 5,

Figure 8 is a fragmentary view in vertical section showing a seat structure pivoted to a carrier,

Figure 9 is a section on line 9—9, Figure 8,

Figure 10 is a top plan view of the seat structure,

Figure 11 is a detail in elevation of a support employed for the seat member of the seat structure, and

Figure 12 is a perspective view illustrating the form of connection for either end of an equalizing means for the seat structure.

The seesaw includes a portable base 1 which consists of a pair of bottom members 2, 3 disposed on a lengthwise edge thereof. The members 2, 3 are arranged in parallel spaced relation and are coupled together by a pair of oppositely disposed combined bracing and spacing bars

4 arranged in parallel spaced relation and provided at their ends with inwardly extending flanges 5 abutting against the inner face of the members 2 and anchored to the latter by the holdfast means 6. Secured to the inner face of the members 2, 3, centrally with respect to the latter, are upstanding oppositely disposed inwardly extending supports 7 formed with vertically disposed parallel spaced upper end terminal portions 8 provided with superposed aligning openings 9, 10, 11 and 11a. Anchored to the bars 4, centrally of the latter, and extending inwardly and upwardly therefrom is a pair of oppositely disposed supports 12 having vertically disposed upper end terminal portions 13 arranged in parallelism and each formed with a pair of openings indicated at 14, 15. The supports 7 and 12 are formed of channel irons.

Arranged between the end terminal portions 8 of the supports 7 and the end terminal portions 50 13 of the supports 12 is a supporting block formed of a pair of oppositely disposed sections 16, 17 of like form. The inner face of each of said sections near its upper and near its lower end is formed with transverse grooves 18, 19 respectively.

tively. The inner face of each of said sections centrally thereof is formed with a transverse groove 20 of greater width and depth than the groove 18 and the groove 19. Between the 5 grooves 18 and 20 each section is formed with a tapered opening 21 extending from its inner to its side outer face and at right angles to said grooves. Each section between the grooves 19 and 20 is formed with a tapered opening 21^a 10 which extends from its inner to its outer side face and is disposed at right angles to the grooves 19 and 20. The end terminal portions 8 of the supporting bar 7 extend above the sections 16, 17. The end terminal portions 13 of the supporting 15 bars 12 have their upper ends positioned below but in proximity to the upper ends of the sections 16, 17. The grooves 18 in the section 16 align to form a circular opening. The grooves 19 in the sections 16, 17 align to form a circular opening. 20 The grooves 20 in the sections 16, 17 align to form a circular opening. Holdfast means 22 contact with the opening 10 in the end portions 8 and with the opening provided by the grooves 18 in sections 16, 17 for connecting the end 25 terminal portions 8 to the sections 16, 17 and for connecting such sections together. Holdfast means 23 coat with the opening 11^a in the end portions 8 and with the opening provided by the grooves 19 in the sections 16, 17 for connecting 30 the terminal portions 8 to the sections 16 and 17 and for connecting sections 16, 17 together. Extending through the openings 14 in the portions 13 and also through the openings 21 in the sections 16, 17 is a holdfast means 24 for connecting 35 the end terminal portions 13 to the sections 16, 17 and for connecting sections 16 and 17 together. Extending through the openings 15 in the end terminal portions 13 and also through the openings 21^a in the sections 16 and 17 is a holdfast 40 means 25 for connecting the end terminal portions 13 to the sections 16 and 17 and for connecting the sections 16, 17 together. The end terminal portions 8 and 13, in connection with the holdfast means 22, 23, 24 and 25, suspend the 45 sectional block at the upper end of the base 1. The sections 16, 17 of the block, when connected together, provide a support for a tubular bearing 26 which extends through the opening formed by the grooves 20 in the sections 16, 17 and 50 through the opening 11 in the end terminal portions 8. The tubular bearing 26 extends laterally in opposite directions from the end terminal portions 8. Mounted in the bearing 26 and of a greater length than the length of the latter is a 55 pivot shaft 27 having reduced terminal portions 28, 29 formed with peripheral threads and carrying securing nuts 30, 31 respectively. The junction of the terminal portions 28, 29 with the remaining part of the shaft 27 forms the latter 60 with peripheral shoulders 32, 33 respectively. Extending through the openings 9 of the end terminal portions 8 is a headed bolt 34 carrying a securing nut 35. The bolt 34 constitutes a pivot which is common to the equalizing means, to be 65 referred to, of the carriers, to be referred to.

The seesaw includes a pair of oppositely disposed carriers 36, 37. The carrier 36 consists of a pair of oppositely outwardly inclined side bars 38, 39 of channel shape cross section. The bars 70 38, 39 are formed with straight inner end terminal portions 40, 41 respectively provided with openings 42, 43 respectively which are seated on the reduced terminal portions 28, 29 respectively of the shaft 27 (Figure 4). The end terminal portions 40, 41 abut the shoulders 32, 33 re-

spectively and overlap and abut the ends of the tubular bearing 26 (Figure 4). The end terminal portions 40, 41 respectively are formed with openings 44, 45 respectively for a purpose to be referred to. The outer ends of the bars 38, 39 5 have mounted therein the squared shank 46 of a coupling 47. The latter includes a tubular apertured part 48 integral with and extended from the outer end of the shank 46. The shank is formed with an opening 49 which registers with 10 openings 50 formed in the bars 38, 39. The shank 46 and the bars 38, 39 are secured together by a holdfast means 51 (Figure 8). The carrier 36 includes an equalizing member 52 of tubular form into the inner end of which extends the 15 shank 53 of a coupler 54 formed with a tubular apertured end part 55 which encompasses the pivot provided by the bolt 34. The shank 53 of coupler 54 is connected to member 52 by the holdfast means 56. The outer end of the member 52 20 has connected therewith a yoke shaped coupler 57 having its arms 58 formed with openings 59. The purpose of couplers 47 and 57 will be presently referred to.

The carrier 37 extends in an opposite direction 25 with respect to carrier 36. Carrier 37 is constructed similar to the carrier 36 with the exception that the inner end terminal portions 60, 61 of the side bars 62, 63 overlap spaced aligning offsets 64, 65, 66 on the outer faces of semi-circular plates 67 formed with openings 68 to provide for the mounting of the plates 67 on the reduced end terminals 28, 29 of shaft 27 (Figure 4). The end terminal portions 60, 61 have openings 68^a at their free ends and also openings 69 which 30 register with the openings 68 extending through offsets 65 and the plates 67 (Figure 6). The end terminal portions 60, 61 are secured against offsets 64, 65, 66 by the holdfast means 70 35 extending through openings 69^a formed in the 40 offsets and the plates. The offsets 64, 65, 66 have beveled side edges and the inner faces of the end terminal portions 60, 61 of the side bars 62, 63 are also beveled whereby said end terminal portions will snugly engage the offsets (Figure 4). 45 The end terminal portions 60, 61 extend beyond the straight edge of the plate 67. Each plate 67 is formed with a pair of spaced oppositely disposed arcuate rows of spaced openings. The openings of one row are indicated at 71 and those 50 of the other row at 72. This arrangement permits either plate to be positioned at either side of a sectional block. The end terminal portions 60, 61 have openings 72^a. The plates and offsets 64, 66 have openings 72^b, 72^c respectively. 55 The openings 72^b, 72^c register respectively with an opening 71 and an opening 72. The openings 68^a, 72^a register with openings 72^b, 72^c respectively. Otherwise than that as stated the construction of the carrier 37 will be the same as 60 that of the carrier 36. The equalizing member of the carrier 37 is designated 73.

The carriers, when the device is in use, move upwardly and downwardly alternately in opposite directions. The normal position of the carriers 36, 37 is as shown in full lines (Figure 1), that is to say, extended at opposite upward inclinations and balanced upon shaft 27. One of the carriers is angularly adjustable relative to the other for decreasing the leverage thereof and by 65 way of example, carrier 36 is shown as being adjustable. The carriers include coacting means for maintaining the adjustable carrier in its adjusted position relative to the non-adjusted carrier. The said coacting means includes the plates 75

67, a selected opening from one of the rows of openings of each plate 67, the openings 44, 45 in the side bars 38, 39 respectively (Figure 4), the headed bolts 73^a, 74 and the nuts 75, 76 arranged 5 on the bolts 73^a, 74. The opening 44 is for registry with an opening selected from one of the rows of openings in one of the plates 67 and the opening 45 is for registry with an opening selected from one of the rows of openings in the 10 other plate 67. The bolts 73^a, 74 are to extend through the registering openings. The nuts 75, 76 are screwed home (Figure 6) whereby the carrier 36 is secured in its adjusted position to the plates 67 and the carriers 36, 37 are connected 15 together for moving in unison.

At the outer end of each carrier a seat structure 77 is provided consisting of an upstanding bracket 78 of substantially duck-like contour formed of a horizontally disposed bottom part 79, 20 an upstanding outwardly curved intermediate part 80 and an inwardly extending top part 81. The bottom part 79 is of materially greater width than top part 81. The intermediate part 80 gradually decreases in width from part 79 to part 25 81 and merges into said parts. The part 79 is of inverted channel-shape in cross section. The part 80 is of channel-shape in sectional plan. The part 81 is of channel-shaped contour in vertical section. The bracket 78 is formed with an 30 opening 82 which extends from the upper portion of part 80 to approximately the transverse center of part 79. The portion of the opening 82 in the part 80 is tapered. The portion of the opening 82 in the part 79 is tapered. The tapered portion of the opening 82 in the part 80 is oppositely disposed with respect to the tapered portion of opening 82 in part 79. The part 81 is bifurcated, 35 as at 83. The arms of the furcations have aligning openings 84. The lower ends of the sides of part 80 have aligning openings 85. The coupler 47 extends between the lower end of part 80. Extending through openings 85 is a pivot bolt 87 carrying a securing nut 88. The coupling 57 extends into the furcation formed in the part 81 40 and carries a bearing sleeve 89. Extending through openings 84 and sleeve 89 is a pivot bolt 90 carrying a securing nut 91. The couplers 47, at the outer ends of the carriers, pivotally connect the carriers to the bottom of the seat structures. The couplers 57, at the outer ends of the 45 equalizing members, pivotally connect said members to the top of the seat structures. The equalizing members function to maintain the bottom parts 79 of the brackets 78 parallel to the 50 ground during the elevating and lowering of the carriers.

Each seat structure includes a seat member 92 formed of an outer part 93, an intermediate part 60 94 and an inner part 95. The part 93 is of greater width and length than that of part 94. The latter is of greater width and length than that of part 95. The part 94 is seated upon the bottom part 79 of bracket 78. The part 95 extends through the opening 82 into the lower end of part 80 of the bracket 78. The part 94 is secured 65 to part 79 of bracket 78 by hold-fast means 96 passing through part 94, the portion of opening 82 in part 79 and clamping against the part 94 and the inner face of part 79 (Figure 8). 70 The couplers 57 include shanks 96 which extend (Figure 8) into the outer ends of the equalizing members. Seated upon each equalizing member over the shank 96 of a coupler 57 is a handle bar 97. The latter has a groove 98 to receive an 75 equalizing member. The latter, shank 96 and

handle bar 97 are anchored together by the hold-fast means 99.

The openings 68^a or 72^a, in connection with openings 72^b or 72^c, openings 44, 45 and bolts 73^a, 74, will provide for the connecting of the carriers together to be disposed horizontally, that is to say, for one carrier to be a horizontal continuation of the other whereby the carriers will be disposed at right angles to the base and not at acute and obtuse angles with respect to the 10 base as shown in full lines, Figure 1.

What I claim is:

1. In a portable seesaw, a base structure, a pair of oppositely disposed tiltable carriers extending from said structure, each including a 15 pair of oppositely outwardly inclined horizontal side bars and a horizontal equalizing member above said bars, a common pivot for said bars mounted in said structure, a common pivot for the inner ends of said members mounted 20 in said structure above the said other pivot, the inner ends of said carriers having coacting interengaging means for detachably connecting them together for moving in unison and to provide for one of the carriers 25 being angularly adjusted relative to the other and to said lower pivot for decreasing the leverage of the adjusted carrier, and a pair of seat structures, each being pivoted at its inner end to the equalizing member and side bars of a carrier. 30

2. In a portable seesaw, a base structure, a pair of oppositely disposed tiltable carriers extending from said structure, each including a 35 pair of oppositely outwardly inclined horizontal side bars and a horizontal equalizing member above said bars, a common pivot for said bars mounted in said structure, a common pivot for the inner ends of said members mounted in said structure above the said other pivot, the inner ends of said carriers having coacting interengag- 40 ing means for detachably connecting them together for moving in unison and to provide for one of the carriers being angularly adjusted relative to the other and to said lower pivot for decreasing the leverage of the adjusted carrier, 45 a pair of seat structures, each having the top of its inner end aligning with an outer edge of a member, detachable means for pivotally connecting the top of the inner end of a seat structure to the outer end of an equalizing member, and 50 detachable means for pivotally connecting the bottom of the inner end of a seat structure to the outer ends of a pair of side bars of a carrier.

3. In a portable seesaw, an upstanding base structure including a vertical block disposed centrally and in proximity to the upper end, an upper pivot supported by said base above said block, a lower pivot supported by, passing through said block and extending laterally in opposite directions relative to said structure, a 60 pair of tiltable oppositely extending carriers, each including a pair of side bars and an equalizing member, said bars being mounted on the extended portions of the lower pivot, detachable means on the inner ends of said equalizing members for 65 pivotally connecting them to the upper pivot in alignment with the top of the block, adjustable means for detachably connecting the bars of one carrier to the bars of the other carrier to provide for the tilting of the carriers in unison and for 70 the angular adjusting of one of said carriers relative to the other and to said lower pivot, a pair of seat structures, detachable means for pivotally connecting the top of the inner end of said seat structures to the outer ends of said 75

members, and detachable means for connecting the bottom of the inner side of said seat structures to the outer ends of said bars.

4. In a portable seesaw, an upstanding base structure including a vertical block disposed centrally and in proximity to the upper end thereof, an upper pivot supported by said base above said block, a lower pivot supported by passing through said block and extending laterally in opposite directions relative to said structure, a pair of tilttable oppositely extending carriers, each including a pair of side bars and an equalizing member, said bars being mounted on the extended portions of the lower pivot, detachable means on the inner ends of said equalizing members for pivotally connecting them to the upper pivot in alignment with the top of the block, adjustable means for detachably connecting the bars of one carrier to the bars of the other carrier to provide for the tilting of the carriers in unison, a pair of seat structures, detachable means for pivotally connecting the top of the inner end of said seat structures to the outer ends of said members, and detachable means for connecting the bottom of said seat structures to the outer ends of said bars, the said means for connecting the inner ends of the bars of one carrier to the bars of the other carrier being so formed to provide for the angular adjusting of one carrier relative to the other and to said lower pivot for reducing the leverage of the adjusted carrier and for securing the adjusted carrier in its adjusted position.

5. In a portable seesaw, an upstanding base structure, a lower pivot carried thereby and extended laterally in opposite directions therefrom, an upper pivot mounted in the upper end of said structure, a pair of oppositely extending carriers, each having a part extending at its inner end into the base and mounted on said upper pivot and a pair of parts straddling the base at their inner portions and mounted on the laterally extended portions of said lower pivot, seat structures pivotally supported from and at the outer ends of the carriers, and coacting interengaging means supported by the carriers for detachably connecting the carriers together to provide for the carriers operating the unison, the said means being so formed to provide for the angular adjusting of one carrier relative to the other and to said lower pivot for reducing the leverage of the adjusted carrier and for securing the adjusted carrier in its adjusted position.

55. 6. In a portable seesaw, an upstanding base structure including in proximity to its upper end a centrally arranged suspended vertically disposed block, an upper pivot carried by the base above and aligning with the block, a lower pivot carried by and extending laterally in opposite directions from the block, a pair of oppositely extending tilttable carriers each including an equalizing member pivotally connected at its inner end with said upper pivot and a pair of side bars straddling the base at their inner ends and mounted on the laterally extending portions of said lower pivot, a plate secured to the inner end terminal portion of each of the side bars of one of the carriers and formed with an arcuate row of spaced openings and with an opening for the passage of the lower pivot, means carried by the inner end terminal portion of each of the side bars of the other carrier and coacting with a selected opening of one of said rows for connecting the carriers together to provide for

the moving of the carriers in unison, said means and rows of openings providing for the angular adjusting of one carrier relative to the other for decreasing the leverage of the adjusted carrier, and seat structures pivotally connected to the outer ends of said equalizing members and bars.

7. In a portable seesaw, an upstanding base structure including in proximity to its upper end a centrally arranged suspended vertically disposed block, an upper pivot carried by the base above and aligning with the block, a lower pivot carried by and extending laterally in opposite directions from the block, a pair of oppositely extending tilttable carriers, each including an equalizing member pivotally connected at its inner end with said upper pivot and a pair of side bars straddling the base at their inner ends and mounted on the laterally extending portions of said lower pivot, a plate secured to the inner end terminal portion of each of the side bars of one of the carriers and formed with an arcuate row of spaced openings and with an opening for the passage of the lower pivot, means carried by the inner end terminal portion of each of the side bars of the other carrier and coacting with a selected opening of one of said rows for connecting the carriers together to provide for the moving of the carriers in unison, said means and rows of openings providing for the angular adjusting of one carrier relative to the other for decreasing the leverage of the adjusted carrier, and seat structures pivotally connected to the outer ends of said equalizing members and bars, said plates having their outer faces formed with spaced aligning offsets, the inner end terminals of the bars secured to said plates overlapping the said offsets.

8. In a portable seesaw, an upstanding base structure of skeleton form including a centrally suspended vertical block and a pair of spaced parallel parts extending above the block, an upper pivot carried by said parts, a lower pivot carried by, passing through said block, and extending laterally in opposite directions relative to said structure, a pair of oppositely disposed tilttable carriers having their inner ends extending between said parts and straddling said structure, said carriers at their inner ends being mounted on said upper pivot between said parts and on the lateral extended portions of said lower pivot, said carriers having coacting detachable, interengaging adjustable means at their inner ends to provide them of the same leverage, for reducing the leverage of one with respect to the leverage of the other and for connecting them together to move in unison, the coacting means of one of said carriers mounted on said lower pivot, and seat structures connected to the outer ends of said carriers.

9. In a portable seesaw, an upstanding base structure, a pair of superposed pivots carried by said structure, the lower of said pivots being extended laterally in opposite directions with respect to said structure, a pair of oppositely disposed tilttable carriers extended from said structure, each carrier including an equalizing member pivotally connected at its inner end with said upper pivot and a pair of side bars straddling said structure, the bars of one of said pairs being mounted at their inner ends upon the extended portions of said lower pivot, the bars of the other pair of bars being mounted adjacent their inner ends upon the extended portions of said lower pivot, seat structures connected to the

equalizing members and said pairs of bars, said pairs of bars having coacting detachable, inter-engaging, adjustable means to provide for said carriers being of the same leverage, for reducing the leverage of one carrier with respect to the leverage of the other and for connecting the carriers together to move in unison, the coacting means of one pair of bars being mounted on the extended portions of said lower pivot.

10. In a portable seesaw, an upstanding base structure including a centrally suspended vertical block and a pair of spaced parallel parts extended above the block, an upper pivot carried by said parts and positioned above said block, 15 a lower pivot carried by, passing through said block and extending laterally in opposite direc-

tions relative to said structure, a pair of oppositely disposed independent tiltable carriers, each including an equalizing member and a pair of side bars arranged below said member, one pair of side bars being mounted at their inner ends upon the extended portions of the lower pivot, the other pair of side bars being mounted adjacent their inner ends on the extended portions of said lower pivot, means carried by the inner end of each equalizing member for pivotally connecting it to said upper pivot within the upper end of said structure, and means carried by the said pairs of bars for adjustably connecting said carriers together.

HARRY F. HUSTED.

15
